UNITED STATES PATENT OFFICE.

JAMES SMITH, OF ANACONDA, MONTANA.

RAIL JOINT.

Application filed October 27, 1922. Serial No. 597,306.

To all whom it may concern:

Be it known that I, JAMES SMITH, a citizen of the United States, residing at Anaconda, in the county of Deerlodge and State 5 of Montana, have invented new and useful Improvements in Rail Joints, of which the following is a specification:

The object of this invention is to produce a means for connecting the confronting ends 10 of railway rails in a manner which will afford a strong and effective joint for the rails, and which will also materially decrease the gap between the rail ends incident to contraction so that substantially a continuous 15 smooth surface over the joint is provided for the wheels of the rolling stock.

To the attainment of the foregoing, and other objects which will present themselves as the nature of the invention is better understood, reference is to be had to the drawings which accompany and which form part 20 of this application.

In the drawings:

Figure 1 is a side elevation of two rails 25 connected in accordance with this invention.

Figure 2 is a top plan view thereof.

Figure 3 is a sectional view on the line 3—3 of Figure 1.

Figure 4 is a sectional view on the line 30 3—4 of Figure 1.

Figure 5 is a sectional view on the line 5—5 of Figure 1.

Figure 6 is a perspective view of one of 35 the joint members looking toward the inner face thereof.

Figure 7 is a similar view, but looking toward the outer face of the joint member.

Figure 8 is a similar view of the rail plate.

Referring now to the drawings in detail, 40 the numeral 1 designates the confronting ends of two railway rails. The ends of the rails are straight, so that the necessity of cutting the same angularly or otherwise is avoided in the employment of my improved joint.

The rails rest on a tie plate 2 which has its edge flanged, as at 3, the said flanges, however, at preferably equi-distance from the ends of the plate being notched, as at 4 to receive the spikes that enter the ties 6. The flange 3 at one side, between the notches 4, has at its inner corner an inwardly directed lip 7, the purpose for which will presently be apparent.

55 The joint sections are each of a similar construction, so that a description of one is

to be considered applicable to the other. Each of the joint sections comprises a base 8, having a depending thickened portion 9 at the center thereof, the said portion 9 being also extended beyond the longitudinal edge of the base 8 and being of a length 60 to be received beneath the lip 7 of the flange 3. Thus it will be noted that the bases proper of the joint members are elevated above the tie plate 2, and the base flanges of the rails when disposed between the outer portions of the flanges 3, on the tie plate 2, underlie and are contacted by the ends of the base 65 of the joint members.

70 From the base 8 of each of the joint members there arises a flange 10. Each flange is centrally formed with an extension in the nature of a crown 11, the said extensions or crowns being of a length equalling that of the thickened extensions 9 on the center of the base. The upper edges of the flanges 10 to the sides of the extension or crown 11 are beveled, whereby the same will correspond to the under faces of the heads of the 75 rails so that the said heads of the rails will rest against these portions of the joint.

Each of the joint members has its inner face in a line with the opposed ends of the crown 11 thereon, thickened as at 12, the said thickened portion projecting below the base, 8, being integrally formed with the central thickened portion 9 of the said base, while the inner ends of the portions 12 are beveled in opposite directions as at 13. 90 These beveled ends are designed for contacting engagement when the joint members are associated.

The flanges of the joint members are provided with openings 14, certain of which 95 being elongated, and certain of which align with the bolt openings in the webs of the rails. There are passed through these openings the usual bolts engaged by the usual nuts. The heads of the spikes 5 it will be noted by reference to the drawings, overlie the base flanges of the rails and contact with the outer flanges of the base of the joint sections, so that the rails are effectively sustained upon the tie plate and the joint sections are held against lateral movement on said plate. The contacting engagement of the edges of the portions 9 of the joint sections with the walls of the flanges 3 also prevent the lateral movement of the joint sections, while in addition to this, the lip 100 105 110 7 on the flange overlying the portion 9 of the

joint section holds the same from both vertical and tilting movement.

Each joint member is rigidly held to one rail end and slideable on the other rail end, to provide for contraction and expansion and also to prevent a gap at either rail end.

Having described the invention, I claim:—

1. In combination, the confronting ends of railway rails, a flanged plate on which the rail ends rest, and ties supporting the plate, of a joint connection for the rails, comprising two similarly constructed sections, each including a base having a central enlargement projecting laterally therefrom, a vertical flange arising from the base of each joint section and being formed with a central extension in the nature of a crown against which the heads of the rails contact, and also having thickened portions on the opposed ends thereof, the confronting faces of which contact, the outer ends of the vertical flanges overlapping the ends of the rails and being secured thereto.

2. In combination, the confronting ends of railway rails, a flanged plate on which the rail ends rest, and ties supporting the plate, of a joint connection for the rails, comprising two similarly constructed sections, each including a base having a central enlargement projecting laterally from the base, in contacting engagement with the flanges and with the rail ends, a vertical flange arising from the base of each joint section having a central extension in the nature of a crown against which the heads of the rails contact, and also having thickened portions on the opposed ends thereof, the confronting faces of which contact, and the outer ends of which contacting the heads and webs of the rails, means for securing the joint sections to the ends of the rails, and spikes securing the plate on the ties and engaging the base flanges of the rail ends and contacting the edges of the base of the joint sections.

3. In combination, ties, a flanged plate resting on the ties having its sides provided with notches adjacent the ends thereof, and one flange between the notches having an inwardly projecting lip, rail ends resting on the plate and having their flanges contacting the flanges of the plate, a rail joint comprising two companion sections, each including a base having its under face centrally enlarged, the said enlargement projecting laterally therefrom to be received beneath the lip of the central portion of the plate flange and having its ends contacting the ends of the base flanges of the rails when the base of the joint members overlie said rail flanges, each of said joint sections having a vertical flange arising from the base and formed with a central enlargement in the nature of a crown, the upper edges of the joint flanges underlying the heads of the rails, and the ends of the heads contacting with the ends of the crowns, each of said joint sections, from the opposed ends of the crown portions thereof having their inner faces thickened to contact with both the heads and webs of the rails, said thickened portions having their confronting faces beveled in opposite directions for contacting engagement, means connecting the joint sections with the rails, and spikes inserted in the notches of the plate to have their heads contact with the base flanges of the rails and with the outer edges of the base flanges of the joint sections.

4. In combination, the confronting ends

of railway rails, a plate on which the rail ends rest, and ties supporting the plate, of a joint connection for the rails comprising two similarly constructed sections, each including a base having a central enlargement projecting laterally therefrom, a vertical flange arising from the base of each joint section and being formed with a central extension in the nature of a crown against which the heads of the rails contact, and also having thickened portions on the opposed ends thereof, the confronting faces of which contact, the outer ends of the vertical flanges overlapping the ends of the rails and being secured thereto.

5. In combination, the confronting ends of railway rails, a flanged plate on which the rail ends rest, and ties supporting the plate, of a joint connection for the rails, comprising two similarly constructed sections, each including a base having a central enlargement projecting laterally therefrom and contacting with the flanges on the plate, a vertical flange arising from the base of each joint section and having a central extension in the nature of a crown, said sections having thickened portions on the opposed ends thereof, the confronting faces of which contact, means for securing the sections to the rail ends, and means for securing the plate on the ties, said means also contacting the edges of the base of the joint sections, to prevent any lateral movement of the said sections.

6. In combination, the confronting ends of railway rails, a flanged plate on which the rail ends rest, of a joint connection for the rails, comprising two similarly constructed sections, each including a base having a central enlargement projecting laterally therefrom, a vertical flange arising from the base of each joint section and having an upward central extension, the outer ends of the vertical flanges overlapping the rail ends and being secured thereto, and means for securing the rails to the plate.

7. The combination with the confronting ends of railway rails, and a flanged plate on which the rail ends rest, of a joint connection for the rails, including a pair of similarly constructed sections, each including a base having a central enlargement projecting laterally therefrom and in contacting engagement with the plate, a vertical flange arising from the base of each joint section and having an upward central extension, the outer ends of the vertical flanges overlapping the ends of the rails and being rigidly held to one rail and slideable on the other.

In testimony whereof I affix my signature.

JAMES SMITH.
